UNITED STATES PATENT OFFICE.

HARVEY W. KLINGENSMITH, OF REYNOLDSVILLE, PENNSYLVANIA.

COMBINED IRONING BOARD AND TABLE.

Application filed February 12, 1926. Serial No. 87,896.

My present invention has reference to a combined ironing board and table, and my object is the provision of a combination article of furniture of this type in which the ironing and sleeve boards are wholly concealed when the device is set up as a table whose top presents a smooth unbroken surface and in which the ironing and the sleeve boards are arranged upon the swingable section of the table top so that the same may be readily brought to operative position by simply swinging the said table top section over one of the fixed top sections.

A further object is the provision of a combination article of furniture of this type in which both an ironing board and a sleeve board are mounted on the under face of a swingable table top section in a manner whereby the ironing board may be moved longitudinally in one direction over the said section, when the device is in one position, and by virtue of such movement will bring a sleeve board to operative position, means being provided for firmly supporting and locking both boards in their said operative positions.

To the attainment of the foregoing and other objects which will present themselves as the nature of the invention is better understood, the improvement further resides in certain features of construction, combination and operative association of parts, a satisfactory embodiment of which is illustrated by the accompanying drawings.

In the drawing:

Figure 1 is a side elevation of the improvement, the ironing board being in set up position.

Figure 2 is a top plan view of the construction as illustrated in Figure 1.

Figure 3 is a transverse sectional view through the device with the swingable table top section swung to align with the remainder of the said top, and whereby the ironing and sleeve board are concealed beneath the top.

Figure 4 is a longitudinal sectional view approximately on the line 4-4 of Figure 3.

Figure 5 is a detail sectional view to illustrate the hinged connection between the fixed and swingable table top sections.

Figure 6 is an end elevation of the ironing board.

When not employed for ironing purposes,

my improved article of furniture is to all appearances and purposes, an ordinary kitchen table. The table includes a substantially rectangular frame 2, supported, at its corners by legs 1. The top of the table is made up of three sections, indicated by the numerals 3, 4 and 5, respectively. The sections 3 and 5 are fixedly secured on the frame 2, while the intermediate section 4 is swingably arranged between the said sections 3 and 5. Pivoted links 5' provide a hinged joint between the fixed table top section 3 and the swingable section 4. The sections 3 and 4 are approximately of the same width, the fixed section 5 being narrower than the said sections 3 and 4. The free edge of the swingable top section 4 is beveled or inclined, as at 9, and is designed to contact with the similarly beveled or inclined inner edge 8 of the fixed top section 5, so that there will be a smooth and even joint between all of the sections when the section 4 is swung on the frame between the sections 3 and 5. Secured centrally on the under face of the swingable table top section 4 there is a longitudinally extending slotted dove-tailed rail 10 for a slideable ironing board 11. The ironing board, on its under face, is formed with a pair of spaced longitudinally extending cleats 12 whose confronting faces are beveled, as at 13, for contacting with the outer angle edges of the rail 10. On one of these cleats 12, there is pivotally secured, as at 14, a latching dog 15. The free end of this dog is designed to be received in a depression providing a keeper 16 in the under face of the swingable table top section 4. The dog has a lip extension 17, whereby the said dog may be brought out of the keeper 16, but the outward longitudinal movement of the ironing board on the track 10 will cause the dog to gravitate into the keeper 16, and it is for the purpose of releasing the dog that the lip 17 is provided.

Secured on the under face of the swingable top section 4, adjacent to one end thereof, there is one of the parallel arms of the substantially U-shaped bracket 18, and secured to the second parallel arm of this bracket there is a sleeve board 19. The arms of the bracket are preferably let in the top section 4 and the sleeve board 19. On the under face of the board there is a transverse cleat 20. Between the confronting faces of

the swingable top section 4 and the sleeve board 19 there is a prop 21.

Fixedly secured, and depending from the inner end of the ironing board 11 and disposed centrally between the cleats 12 there is a plate or bracket 24. Having one end fixed in the prop 21 and extending through an opening in the plate or bracket 24 there is a rod 25. This rod projects a suitable distance beyond the prop and has an outer headed end 23.

When the ironing operation is completed and the device is to be employed as a table, the ironing board 11 is slid inwardly over the table top section 4 and in its movement will contact with the prop 21 to move the latter against the center of the substantially U-shaped bracket 18. The movement of the prop will, of course, exert a pull on the rod 22. The inner end of the ironing board is now arranged beneath the sleeve board 19, and the ends of the ironing board are spaced approximately the same distance from the ends of the table top section 4. The table top section 4 is then swung to close the gap between the table top sections 3 and 5 and thus house the ironing board within the table. When the ironing and sleeve board are desired for use the hinged table top section 4 is swung over and rests upon the fixed table top section 3. The ironing board 11 is then slid outwardly on the table top section 4, the rail 10 and cleats 12 guiding the said board 11 in such movement. The dog 15 will automatically gravitate into its keeper opening 16, and the outward movement of the ironing board 11 will cause the headed end 23 of the rod 25 to contact with the plate or bracket 24, drawing or imparting a longitudinal movement to the said rod

and sliding the prop 21 on the under face of the sleeve board 19 to contacting engagement with the cleat 20 and thereby effectively supporting the sleeve board. Because of the inclined or beveled contacting edges of the cleats 12 and the rail 10 the tilting of the projected end of the ironing board will be prevented.

The simplicity of my construction, and the advantages thereof will, it is believed, be perfectly apparent to those skilled in the art to which this invention relates when the foregoing description has been carefully read in connection with the accompanying drawings but it is to be understood that I do not wish to be limited to the precise features of construction herein set forth, as the invention is to be limited only to the scope of what I claim.

Having described the invention, I claim:—

A table having its top made up of sections, one of said sections being hingedly connected to one of the sections and adapted to be swung over said section when in operative position, a rail having beveled edges centrally fixed on the under face of the hinged section, an ironing board arranged over the rail, a pair of spaced cleats on the under face of the ironing board having their inner edges beveled to slidably engage with the beveled edges of the rail to hold the board on the swingable top section to permit of longitudinal movement of said board on said top section, and latching means for limiting the outward sliding of the board on the said table top section.

In testimony whereof I affix my signature.

HARVEY W. KLINGENSMITH.
